FIG-3

INVENTOR=
J. B. SCOLPONETI

By Miguel Brown Lundy May
ATTORNEYS

UNITED STATES PATENT OFFICE.

JOHN B. SCOLPONETI, OF BOSTON, MASSACHUSETTS.

GARMENT-SLEEVE.

1,214,228.

Specification of Letters Patent. Patented Jan. 30, 1917.

Application filed June 23, 1915. Serial No. 35,775.

To all whom it may concern:

Be it known that I, JOHN B. SCOLPONETI, of Boston, in the county of Suffolk and State of Massachusetts, have invented certain new and useful Improvements in Garment-Sleeves, of which the following is a specification.

This invention has for its object to provide a sleeve for coats and other garments adapted to be adjusted as to its length without the necessity of ripping the outer portion or body of the sleeve from the lining, and to have the adjusted length made permanent with the minimum expenditure of time and labor.

The invention consists in the improvements which I will now proceed to describe and claim.

Of the accompanying drawings forming a part of this specification: Figure 1 represents a perspective view of a portion of a coat sleeve embodying my invention, the sleeve being at its maximum length, and provided with a vent, a portion of the sleeve being turned back; Fig. 2 represents a view similar to Fig. 1, showing the sleeve shortened and as it appears before one of the edges of the vent is folded inwardly; Fig. 3 represents a view similar to Fig. 2, showing one of the edges of the vent folded inwardly; Fig. 4 represents a section on line 4—4 of Fig. 1, the sleeve being at its maximum length; Fig. 5 represents a view similar to Fig. 4, showing the sleeve shortened to its desired operative length.

The same reference characters indicate the same or similar parts in all the views.

In the drawings, 12 represents the body or outer portion of a coat sleeve, and 13 the inner portion or lining thereof, each of these parts being a tube of suitable fabric made longer than the desired length of the sleeve. The lining 13 is of substantially the same length as the body 12, and the outer ends of the body and lining are united to form a finished sleeve-end 14, preferably by forming narrow folds on said outer ends and uniting the folded portion by a line of stitches 15 extending around the sleeve, the construction of the sleeve-end being such that it is permanently finished and requires no subsequent finishing operation.

To reduce the sleeve to the desired operative length its outer end portion is turned inwardly, as shown by Figs. 2, 3, and 5, to form an internal cuff 16 and a neck 17 con-

necting the cuff with the body of the sleeve, said neck constituting the end of the sleeve and being suitably reduced in thickness by pressing the sleeve after the cuff is formed. 60

It will be seen that the body 12 and lining 13 are united at the finished sleeve-end 14. The operation of turning the surplus portion of the sleeve inwardly, simultaneously takes up the surplus of both body and the 65 lining, so that by suitably securing the finished sleeve-end 14 within the sleeve a satisfactory and durable sleeve of the desired length is provided.

The finished sleeve-end 14 may be confined within the sleeve by suitable fastening means of simple character, such as ordinary garment hooks 18 and corresponding eyes 19, as indicated by Fig. 1, or by stitches applied at suitable intervals to connect the 70 sleeve-end with the sleeve. There may of course be any desired number of hooks and eyes, the eyes being secured within the sleeve after the final length of the sleeve is 75 determined. 80

It will be seen that the finished sleeve-end 14 does not have to be disturbed or ripped during the operation of securing it within the sleeve, and that the lining 13 is taken up with the body 12, the lining at all times 85 remaining in a smooth condition within the body and cuff.

The sleeve is provided with a vent at the outer end of the usual longitudinal inner seam 20, which extends along the inner or under side of the sleeve. The said seam terminates at a point at some distance from the outer end of the sleeve, said point, which is at the outer end of the seam, being indicated by 90 the reference numeral 21. The edges 22 and 23 of the portion of the sleeve extending from the end of the seam 20 form a vent, and are suitably finished like the sleeve-end 14, or otherwise. The edge 22, which is an 95 extension of the inner edge of one of the portions united by the seam 20, is turned outwardly before the operation of forming the cuff 16, as indicated by Fig. 1. After the cuff 16 is formed the edge 22 is folded 100 inwardly under the edge 23 to take up the surplus material and form a neck or fold 24 (Fig. 3) which is flush with the edge 23. The fold 24 and edge 23 form the margins 105 of a vent of variable length and are preferably connected by concealed internal stitches 110 to prevent the vent from opening.

The neck 17, forming the outer end of the

adjusted sleeve, is spaced from the outer end of the seam 20, as shown by Fig. 2.

Having described my invention, I claim:

5 A vented coat sleeve composed of a body and a lining of substantially the same length as the body and stitched to the outer end thereof to form a finished sleeve end, the sleeve being formed with a longitudinal inner seam, which is shorter than the operative length of the sleeve, leaving disconnected vent-forming longitudinal edges

which are finished between the outer end of said seam and the outer end of the sleeve, the sleeve end being folded to form a neck which may be variably spaced from the 15 outer end of the inner seam to vary the length of the sleeve and of the vent, one of said vent-forming edges being folded under said end.

In testimony whereof I have affixed my 20 signature.

JOHN B. SCOLPONETI.
